US00D960914S

(12) **United States Design Patent** (10) **Patent No.:** **US D960,914 S**
(45) **Date of Patent:** **** Aug. 16, 2022**

(54) **DISPLAY PANEL OR PORTION THEREOF
WITH A GRAPHICAL USER INTERFACE**

(71) Applicant: **MAGIC LEAP, INC.**, Plantation, FL (US)

(72) Inventors: **Lorena Pazmino**, Wilton Manors, FL (US); **Karen Stolzenberg**, Fort Lauderdale, FL (US); **Brian Everett Meaney**, Parkland, FL (US); **Andrea Isabel Montoya**, Plantation, FL (US); **Gregory Minh Tran**, Miami, FL (US); **Amy Dedonato**, Maumee, OH (US)

(73) Assignee: **Magic Leap, Inc.**, Plantation, FL (US)

(**) Term: **15 Years**

(21) Appl. No.: **29/829,269**

(22) Filed: **Mar. 3, 2022**

CLAIM

The ornamental design for a display panel or portion thereof with a graphical user interface, as shown and described.

DESCRIPTION

The sole FIGURE is a front view of a display panel or portion thereof with a graphical user interface showing our design.

The outermost broken line rectangle illustrates a display panel or portion thereof that forms no part of the design. The remaining broken lines, including all text, illustrate portions of the graphical user interface and form no part of the design.
